CHICAGO POTTERY COMPANY, OF CHICAGO, ILLINOIS, A CORPORATION OF NEW
JERSEY.

CLOSET-BOWL.

1,342,499.

Specification of Letters Patent. Patented June 8, 1920.

Original application filed January 22, 1918, Serial No. 213,131. Divided and this application filed February 1, 1919. Serial No. 274,402.

To all whom it may concern:

Be it known that we, FREDERICK J. CLIFFORD and LINDON A. PERRY, citizens of the United States, residing in Chicago, in the county of Cook and State of Illinois, have invented a new and useful Improvement in Closet-Bowls, of which the following is a specification.

This invention relates in general to the manufacture of closet bowls and has for its object broadly the economic provision of a bowl of improved manufacture and construction. This application is a division of our application Serial No. 213,131, filed January 22, 1918; for improvements in closet bowls and the art of forming same.

A principal object of the present invention is the provision of a process more simple than the present generally used process termed "overcasting," and including first the casting of certain minor parts of the closet body and later the casting about these parts of the remainder of the body. The use of the overcasting process has resulted in considerable useless expense which our present invention aims to eliminate. The casting of material upon previous cast material in this process not infrequently results in cracking because of the difference in degree of dampness, the consequent uneven drying setting up cracking strain in the material. Moreover, the inner drier parts tend to absorb moisture from the outer parts and thus interfere with the normal drying and shrinkage. On this account the overcasting process requires both a high degree of skill in the preparation of the slip and also in the casting operation. It is therefore a purpose of the present invention to provide a process which will not require the casting of one part upon another and the provision also of a process wherein the operations may be successfully performed by the usual available labor and without the necessity of the high skill and care needed in the overcasting process.

A still further purpose of the invention is the provision of a process for casting closet bowls and the like which will insure even, rapid drying of the body after being cast and this without danger of the cracking of the body through uneven shrinkage.

Another object of the invention is the provision of a closet bowl having a large

water surface and a deep water seal and at 55 the same time a powerful siphon action at the trap.

A still further object of the invention is the provision of a closet bowl wherein all of the parts will be accessible to the persons 60 working thereon after casting, in order that any slight defects or imperfections may be corrected as the work progresses.

Numerous other objects and advantages of the invention will be apparent as it is 65 better understood from the following description when considered in connection with the accompanying drawing illustrating a preferred embodiment thereof.

On the drawing,—

Figure 1 is a vertical front-to-back section taken through a closet bowl embodying our present invention;

Fig. 2 is a section taken substantially on the line 2—2 of Fig. 1;

Fig. 3 is an inside view of one of the outer main mold parts;

Fig. 4 is a similar view showing said part with the core mold part set in;

Fig. 5 is a section taken substantially on the line 5—5 of Fig. 4;

Fig. 6 is a perspective view of the female tongue forming mold part;

Fig. 7 is a similar view of its companion; and

Fig. 8 is a perspective view of the partition tongue before assembling in the closet bowl as will be later described.

For the purposes of illustrating our invention we have shown a closet bowl of the 90 general siphon action wash-down type, in which said invention is embodied. It will be manifest, however, as the invention is better understood that it is by no means restricted to closet bowls of this type or 95 character.

Referring to Fig. 1, reference character 10 designates the outer encompassing and upright wall of the body of the bowl and extends up from the base 11 to which it 100 is joined at 12. Said base 11 has an outlet 13 adapted for connection with the soil or waste pipe. Upon the upper edge of the main bowl part 10 is provided a rim part 14 of any usual or preferred construction, 105 being shown as having a flushing inlet 15 into the inside 16 of the rim and jet outlets 17 for flushing. The bowl is provided with

a siphon trap comprising a horizontal passage 18 extending from the rear toward the front, an up-passage 19 extending sharply up near the front, a down-passage 20 at the front, and a horizontal return passageway 21 communicating with the outlet 13.

It will be noted from the drawing that the outer wall of the bowl and the partitions forming these passageways are all of single wall construction and of substantially uniform thickness. This construction is provided by casting the body with a web 22 closing the space within the outer wall 12. This web is connected in the present instance at the rear of the bowl at 23 with the rear portion of the outer wall and thence extends substantially horizontally to 24 adjacent the front part of the closet. From the point 24 the web extends up at almost a right angle, being curved into substantial parallelism with the front part of the wall, it being understood, however, that these parts merge at the sides. The web extends, when the body of the bowl is cast, up to a point 25 where it joins the outer bowl wall. The portion indicated by dotted lines 26 is cut out with a knife or other implement while the body of the bowl is still soft and a tongue or basin forming partition 27 is inserted connecting at the point 25 with the front wall and extending down in engagement with said wall to its rear end. This tongue is shown in detail in Fig. 8, and it will be understood that all of the edge from the adjacent points 28 around its remote end are in contact with and merge into the adjacent face of the outer wall.

The outlet of the basin is formed between the concave edge 29 between the points 28 and the inner face of the outer wall. The tongue 27 is provided with a beveled edge 31 in order that the union between this edge and the inner face of the outer wall can be neatly and expeditiously made without the employment of a substantial amount of connecting material. Inasmuch as the trap forming spoon or partition and the basin forming partition or tongue are of single thickness it is possible to reduce the space occupied by the trap and to give to the trap forming spoon and to the tongue the shape shown, permitting the tongue 27 to be sharply downwardly inclined and the location of the parts to be such that a large water surface and deep water seal is provided within the bowl to minimize soiling and sewer gases.

Particular attention is directed to the shape of the trap forming spoon which provides, as will be evident upon viewing the drawing, a sharp strong siphon action greatly increasing the efficiency of the bowl in service and making it difficult to clog,

and the trap can be provided without requiring that the outer wall be bulged at any points with resulting depressions that must be closed by panels or left in unsightly conditions.

The molds for making this bowl are shown in Figs. 3 to 7, only the mold parts required for the body being shown since our present invention does not concern itself particularly with the provision of base and rim parts.

Viewing Figs. 3, 4 and 5 it will be noted that the main mold parts comprise two outer companion mold parts 41 and 42 which are substantial duplicates of each other and determine the outer surface of the outer wall of the bowl and of course are given the corresponding internal superficial construction. The core part comprises a rim 43 adapted to rest upon the jointed mold parts 41 and 42 and having a body 44 extending down into the opening between them but not reaching the bottom. The rear side 45 of this mold part is spaced from the adjacent surface 46 at the rear of the molds a distance equal to the thickness of the outer wall at this point and the forward face 47 of the core part is spaced from the adjacent face 48 of the outer mold parts a distance greater than the thickness of the outer wall at the front by the thickness of the spoon member and by a distance equal to the passageway 20, the two surfaces approaching each other at 49 to provide the outer wall part 51 as indicated in Fig. 1. The main mold part therefore provides a single wall at the rear of the closet and a double wall adjacent the front, the edges of the double wall merging into the single wall at the sides and top of the passageway. The core provides both the horizontal and upright parts of the spoon member, it being understood that slip is poured into the recess 52 of the core part and flows out through a hole 53 into the space to receive the casting.

In Figs. 6 and 7 the mold parts for the tongue 27 are shown consisting of a lower part 54 and an upper part 55 providing a space between them equal to the thickness of the tongue 27.

It is believed that only a brief further description of the process will be necessary in view of the earlier description. The mold parts 41, 42 and 44 are assembled as shown in Fig. 4 and slip is poured into the mold. At or about the same time the mold parts 54 and 55 are joined and other slip poured between them. These two pouring operations provide the body of the bowl and after this casting is complete the part indicated by dotted lines 26 is cut away by a knife or other suitable instrument and the tongue 27 positioned, the contacting surfaces being provided with slip to make the parts properly join. The edges engaging the inner

surface of the outer wall part of the body are then worked into the inner surface of the wall by molding so that the whole inside of the basin presents a smooth unbroken 5 curve. Should any slight lines of juncture appear as a result of these operations they are within the bowl where they are not readily detected, particularly after glaze has been applied.

10 It is thought that the invention and many of its attendant advantages will be understood from the foregoing description, and it will be apparent that various changes may be made in the form, construction and 15 arrangement of the parts without departing from the spirit and scope of the invention or sacrificing all of its material advantages, the form hereinbefore described being merely a preferred embodiment thereof.

20 We claim:

1. The process of making a closet bowl which includes the following related steps; casting the outer body wall and the trap forming spoon, and thereafter positioning a 25 basin forming tongue or partition above said spoon.

2. The process of making a closet bowl which includes the following related steps: casting the vertical walls of the body and a 30 web connecting said walls and forming said web into a trap forming spoon.

3. The process of making a closet bowl which includes the following related steps: casting the vertical walls of the body and 35 a web connecting said walls and forming said web into a trap forming spoon by cut-

ting away a part of said web to provide a trap passage therethrough.

4. The process of making a closet bowl which includes the following related steps: 40 casting the outer vertical walls with a cross connecting web, the main part of which is shaped to provide a trap forming spoon, cutting away the material of said web to leave a trap forming spoon, and separately 45 casting a tongue or partition and positioning the same above said spoon to form the bottom of the bowl basin and the top of the up-passage of said trap.

5. The process of making a closet bowl 50 which includes the following related steps: the casting of the outer walls of the bowl with a cross connecting web, the cutting away of said web to provide a passage therethrough and to form a partition extending 55 part way across the bowl, and casting separately a second partition and positioning said partition to extend part way across the bowl in the opposite direction, one of said partitions forming a part of the bowl basin 60 and the other the trap forming spoon.

6. A set of molds for forming a closet bowl, comprising outer mold parts, a core part extending into and part way through said outer mold parts, said outer mold parts 65 and said core part forming together the outer vertical wall of the bowl and the trap forming spoon integral therewith, and molds for forming a partition tongue fitting said outer mold wall above said trap.

FREDERICK J. CLIFFORD.
